UNITED STATES PATENT OFFICE

ERNEST GEORGE TODD, OF BRUSSELS, BELGIUM

MILL FOR GRINDING PAINTS, INKS, ENAMELS, AND OTHER VISCOS MATERIALS

Application filed September 21, 1929. Serial No. 394,357.

The object of the present invention is to provide an improved mill for grinding paints, inks, enamels and other viscous materials, of which the construction is simplified and which will have a maximum output.

A grinding mill chiefly comprises a grinding roller cooperating with a rectilinear grinding block, and a feed hopper arranged above the roller, particular means being provided for regulating the pressure of the grinding block.

An object of the invention is to provide a particularly strong and reliable mechanism for imparting a reciprocating movement to the grinding block, said movement being derived from the rotary movement of the grinding roller, but being preferably not in timed relation with the latter movement.

Another object of the invention is to provide in combination with said mechanism for reciprocating the grinding block, a mechanism for lifting the feed hopper together with the grinding block and its actuating mechanism, for the purpose of allowing the various parts of the machine of being easily cleaned.

According to the invention, it is possible to vary the speed of the reciprocating movement of the grinding block and thereby always to cause the latter to move at the speed required by the material to be treated.

The invention will be described hereafter with reference to the figures of the accompanying drawings, which illustrate, merely by way of example, an embodiment of the invention.

Fig. 1 is a side view of the machine, seen in the direction of arrow F of Fig. 2 and showing the means for lifting the feed hopper and grinding block;

Fig. 2 is an elevation sectional view of the left half of the machine, also showing the means for lifting the feed hopper and grinding block;

Fig. 3 is partly a longitudinal sectional view through the grinding block, on line A—B of Fig. 4, and partly a longitudinal view in the direction of arrow E of Fig. 4;

Fig. 4 is, on a greater scale, a transverse section through the grinding block, on line C—D of Fig. 3.

With reference to these figures, the mill comprises a roller 1, slidably fixed on a shaft 2 and actuated to have a rotary movement, for instance by a fast and loose pulley device. Above the roller or cylinder 1, is arranged a feed hopper 4 and laterally a rectilinear grinding block 5. The ground material is collected by a scraper and directed over a slope 6. The elements are supported in a frame 7. The pressure of the grinding block 5 on the cylinder 1 is adjustable by means of a particular device, which can be operated while the machine is running and which will be described hereafter.

Referring more particularly to Figs. 3 and 4, the grinding device comprises an elongated casing 8 of U-shaped cross section and made of cast iron or any other suitable material. In this casing is adapted to slide longitudinally a sliding member 9. The reciprocating movement of this slide member 9 is obtained with a device comprising cams 10 arranged at both ends of the sliding member 9. These cams 10 are driven by toothed wheels 11 and 12 located at both ends of the grinding roller 1. The toothed wheel 11 brings about the rotation of shaft 13 on which is keyed the worm 14, which meshes with the helically toothed wheel 15, mounted on shaft 16, upon which is keyed the cam 3. 80

It will be easily understood that by replacing the toothed wheels 11 and 12 by other toothed wheels, it is possible to impart different movements to the worms 14 and the wheels 15, which, in turn, rotate the cams 3 at different speeds. It is thus possible to reciprocate the sliding member 9 at any required speed. The sliding member 9 is centrally provided with a longitudinal slot 17, in which is accommodated the rectilinear grinding block or bar 5, which comes in contact with the roller 1. The grinding block 5 is held in its position in contact with the roller 1, by means of pressure screws 18, which pass through the pressure bar 19, which is itself 95 pressed against the sliding member 9 by pressure nuts 20 arranged at the ends of the sliding block. The pressure screws 18 are provided with winged heads 21 and may be locked against rotation by lock nuts 22.

In order to maintain the grinding block 5 against the smooth face 23 of the sliding member 9, rollers or idlers 24 have been provided to press against the grinding block 5 and they are maintained in this position by pressure screws 25 passing through a slot 26 formed in the casing 8. These slots have a length which is equal or greater than the stroke of the sliding member 9. The pressure screws 25 may be regulated from the outside by means of milled knobs. Recesses or grooves 9' may be provided in the sliding member 9 to reduce the friction against the walls of the casing 8.

The whole combination of hopper and grinding block with its sliding member and casing is mounted upon lateral supports 27. The hopper rests on the lateral supports 27 with its lugs or lateral flanges 28, spacing bars 29 being interposed. As is well known in the art, it is thus possible to adjust the vertical position of the hopper 4, so that it can be placed at a desired distance from the roller.

The casing 8 for the grinding block 5 is provided at both ends with a flat portion 8' which comes to rest on a flat surface of the lateral supports 27 and which is secured thereon by four bolts 27'. The lateral supports 27 which support the hopper and the grinding block with its regulating means rest normally on the uprights 30 of frame 7 and they can be fixed in this position by means such as swivelling bolts 31 with pressure nuts 32. Such a connecting device ensures the necessary pressure for the grinding operation when the machine is running, whilst it allows at the same time a rapid release by unscrewing the four nuts 32, whereby the superstructure of the machine is freed for the purpose of cleaning the various parts of the mill.

For this purpose, the upper elements of the machine, when they are released from the pressure connection 31-32, are lifted by means of a combined construction, which will be now described. The lateral supports or bridges 27 are supported by standards or columns 33, which are adapted to slide vertically in corresponding guide ways provided on the inner surfaces of the lateral uprights 30 of the frame. These guide tracks will be, for instance, dovetailed tenons 34 formed on said inner face of the uprights 30, on which slide mortises 35 having the same shape. At their lower ends, said standards 33 are connected to each other by a transverse bar 36, which completes with the bridges 27 what will be termed hereafter the lifting frame of the hopper.

These lifting frames rest with interposition of rollers or idlers 37 upon cams which may be, for instance, eccentric discs 38 keyed upon a shaft 39.

It will be understood that, by rotating said shaft 39 by means of an appropriate device,

such as for instance a crank 40, the shank of which bears a pinion 41 meshing with a second pinion 42 keyed on shaft 39, the lifting frame of the hopper may be raised through the medium of cams 38.

In order to facilitate the maintenance of the hopper in both lifted and lowered positions, it is of great avail to provide at convenient points of the cams 38, notches 43, which may be engaged by said idlers 37. Various equivalent devices may, of course, be used to obtain the same effect, as, for instance, the lifting frames may be operated by means of a rack upon which will act pinions driven by a crank.

The elements of the lifting mechanism may be protected by a casing 44, constituting an oil tank for lubricating purposes.

In the machine illustrated, a mechanism for reciprocating the grinding block is provided at both ends of the rollers; such disposition is preferable owing to the considerable friction between the roller 1 and the block 5. It is obvious that one of these mechanisms may be replaced by a return spring of appropriate strength.

It is obvious that with the device according to the invention, the reciprocating movement of the grinding block need not be in timed relation with the rotary movement of the roller and it is preferable that there should be no timed relation between these movements, as in this case the peripheral surface of the roller will be more perfectly used for grinding and less rapidly worn.

The device as described is characterized by its great simplicity and solidity of construction, as also by the fact that it can be fitted on grinding mills of various types. It permits of easy regulation for any kind of material to be treated by merely interchanging the pinions of the mechanism for reciprocating the grinding block.

I claim:

1. A mill for grinding paints, inks, enamels and other viscous materials, comprising a roller actuated to have a rotary movement, a feed hopper adjustably mounted above the roller, a casing fixed to the frame and extending longitudinally of the roller, a sliding member adapted to reciprocate longitudinally in said casing, a grinding block fixed to said sliding member and adapted to contact the roller along its whole length, cams adapted to reciprocate said sliding member, means driven from the roller to rotate said cams, a number of pressure screws adapted to press the block against the roller and reciprocating with the sliding member, winged heads for adjusting the pressure of said screws, a number of idlers adapted to press a lateral face of the block against a smooth surface of the sliding member and means to adjust the pressure of said idlers.

2. A mill for grinding paints, inks, en-

amels and other viscous materials, comprising a roller actuated to have a rotary movement, a feed hopper adjustably mounted above the roller, a casing fixed to the frame and extending longitudinally of the roller, a sliding member adapted to reciprocate longitudinally in said casing, a grinding block fixed to said sliding member and adapted to contact the roller along its whole length, cams adapted to reciprocate said sliding member, means driven from the roller to rotate said cams, means to adjust the pressure of the grinding block on the roller, bridge pieces transversely mounted at the ends of the frame to which said casing and said hopper are secured, a lifting frame supporting each of said bridge pieces and adapted to slide vertically in the frame to lift and lower said bridge pieces and means to move said lifting frames up and down.

3. A mill for grinding paints, inks, enamels and other viscous materials, comprising a roller actuated to have a rotary movement, a feed hopper adjustably mounted above the roller, a casing fixed to the frame and extending longitudinally of the roller, a sliding member adapted to reciprocate longitudinally in said casing, a grinding block fixed to said sliding member and adapted to contact the roller along its whole length, cams adapted to reciprocate said sliding member, means driven from the roller to rotate said cams, means to adjust the pressure of the grinding block on the roller, bridge pieces transversely mounted at the ends of the frame to which said casing and said hopper are secured, a lifting frame supporting each of said bridge pieces and adapted to slide vertically in the frame to lift and lower said bridge pieces, cams to move said lifting frames up and down, idlers interposed between the cams and the lifting frames, peripheral notches in the cams for the engagement of said idlers in the lifted and lowered positions of the lifting frame and means to rotate said cams.

In testimony whereof I signed hereunto
my name.

ERNEST GEORGE TODD.
